ABSORPTION TYPE REFRIGERATING
SYSTEM

Albert R. Thomas, New York, N. Y., assignor to
Electrolux Servel Corporation, New York, N. Y.,
a corporation of Delaware

Application December 21, 1932, Serial No. 648,148

28 Claims. (Cl. 62—119.5)

This invention relates to absorption type refrigerating systems in which circulates an auxiliary pressure equalizing fluid and more particularly to systems of this type cooled by air.

5 In air cooled refrigerating systems of this type, it is highly desirable for best operating efficiency to have the internal pressure vary with the temperature of the cooling air. Since the air temperature is subject to wide variation, if the pressure is fixed to correspond with the most extreme temperature, the advantage of lower condensing pressure required under average conditions is sacrificed. The condensing pressure necessary under average conditions allows high thermal 10 efficiency and the corresponding low boiler temperature reduces the rate of internal corrosion.

It has heretofore been proposed to provide an enlarged chamber in the condenser vent line for the storage of excess auxiliary fluid which is displaced into the gas circuit upon rise in the condenser temperature. It is a purpose of this invention to use such a storage chamber, herein referred to as a pressure vessel, and effect a greater variation in pressure without increasing 25 the volume or size of the vessel.

It is further among the objects of this invention to effect a more rapid change in pressure and utilize the storage or pressure vessel as an extension of the condenser so that it functions as such 30 at high ambient temperatures when it is filled principally with refrigerant vapor.

The type of refrigeration system under consideration comprises, in general, an evaporator and an absorber connected in a circuit for an inert gas as an auxiliary pressure equalizing fluid. From a generator containing a solution of refrigerant in a liquid absorbent, liquid refrigerant is distilled off and conveyed to the evaporator, and the resulting weak solution is circulated through 35 the absorber. In the evaporator, the liquid refrigerant evaporates while diffusing into the inert gas, and in the absorber, refrigerant vapor is absorbed out of the inert gas into solution with the absorbent. The above mentioned objects of my invention may be attained by providing an auxiliary circuit communicating with the inert gas circuit in such a manner that there circulates in the auxiliary circuit an excess quantity of inert 40 gas which, due to circulation thereof during normal operation of the system, is at substantially the same partial pressure as gas flowing from the absorber to the evaporator. Suitable provision is made for automatically displacing gas from the 45 auxiliary circuit into the main circuit to increase

the pressure in the latter, and thus the total pressure in the system.

The nature of my invention and the objects and advantages thereof will be more fully understood from consideration of the following description taken in connection with the accompanying drawing in which the figure shows schematically a refrigerating system of the pressure equalized absorption type embodying the present invention.

The refrigerating system shown in the drawing 60 is similar to that disclosed in my copending application Serial No. 613,387. Briefly, in the generator 10 a refrigerant vapor is expelled from solution in an absorption liquid by heat. For purposes of description, ammonia may be the refrigerant and water the absorbent. Ammonia vapor from the upper part of the generator 10 flows in conduit 12 through a rectifier 11 to the upper part of a separating vessel 13. The latter 70 also acts as a low temperature rectifier for gas flowing in conduit 12. From the separator, the vapor passes to an air cooled condenser 14 where it is liquefied, the liquid flowing through conduit 15 into the upper part of a vessel 16. From the lower part of vessel 16, liquid ammonia flows 80 through conduit 17 to the absorber cooling coil 18 which is constructed and arranged to constitute thermosiphon conduit.

Cooling of the absorber is accompanied by vaporization of some of the ammonia in coil 18, the 85 vapor raising liquid ammonia upwardly through conduit 19 back to the separator 13 by thermosiphonic or gas lift action. The lifting vapor then passes back into the condenser and the liquid ammonia which accumulates in the lower part of 90 the separator 13 overflows through conduit 20 into the evaporator 21 where it evaporates by diffusion into an auxiliary pressure equalizing fluid such as hydrogen which circulates between the absorber 22 and the evaporator 21 by way of the 95 gas heat exchanger 23.

Weak absorption liquid flows from the lower part of the generator 10 through a liquid heat exchanger 24 to the absorber 22 where it absorbs 100 ammonia out of the gas mixture. The enriched absorption liquid accumulates in the lower part of the absorber from where it flows back to the generator 10 through the liquid heat exchanger 24, being raised from the surface level of liquid in the absorber to the surface level of liquid in the generator by a thermosiphon or gas lift element 25 due to vapor formed by heating the lower part of the element in a well known manner.

In accordance with the present invention, there is provided a closed vessel 26 connected to the 110

gas circuit through conduits 27 and 28. These connections, as shown, are made to the gas heat exchanger, conduit 27 connecting the upper end of the pressure vessel 26 to the "weak" gas portion of the circuit and conduit 28 connecting the lower end of the pressure vessel to the "rich" gas portion of the circuit. The path formed by conduit 27, pressure vessel 26, and conduit 28, in this embodiment, is in effect a shunt across the gas circuit between the evaporator and absorber. It is apparent, however, that conduit 27 may be connected either to the weak or rich side of the gas circuit. A connection to the weak gas side will be more effective in increasing the amount of hydrogen stored in the auxiliary circuit at low room temperature, as hereinafter set forth, but on the other hand connection to the rich gas side is more desirable in preventing the possibility of introducing ammonia vapor into the weak gas when the unit is operating near maximum pressure.

In a condenser vent chamber as heretofore proposed, the amount of hydrogen at low air temperatures is from 30-40% of the chamber volume as the temperature difference between the condenser and chamber is only around 15° C. In the gas circulation circuit of the refrigerating system there is a gas mixture containing more than 90% hydrogen and by providing in connection with the condenser vent chamber or pressure vessel 26, an auxiliary circuit communicating with the gas circuit, there circulates through the pressure vessel, when condensation is not taking place therein, this gas mixture which is nearly all hydrogen.

Circulation occurs upwardly through conduit 27 and downwardly through conduit 28 due to the greater specific weight of the gas in the pressure vessel 26 and conduit 28 than that in conduit 27. When the concentration of hydrogen in the pressure vessel 26 approaches that in the gas circuit, circulation becomes very slow, that is, just enough to remove the excess ammonia vapor coming from the residual gases in condensation.

As the air temperature increases and the pressure becomes insufficient for complete condensation, the excess ammonia vapor flows through conduit 29, conduit 28, and a liquid trap 30 to the absorber. Conduit 29 constitutes a vent from the condenser to the auxiliary circuit 26, 27, 28, 30. Since conduit 28 and the trap 30 are exposed to the air, condensation of the ammonia vapor occurs and the liquid collects in the trap stopping circulation in this direction causing the ammonia vapor to flow into the pressure vessel 26 displacing the hydrogen therefrom through conduit 27 into the gas circuit, thus increasing the pressure in the latter. During high ambient temperature the pressure vessel 26 functions as a continuation of the condenser, the condensate draining through conduit 29 to the vessel 16 where it joins refrigerant liquid flowing toward the evaporator.

When the temperature of the air again decreases, condensation no longer occurs in conduit 28 and the liquid ammonia evaporates from the trap 30 by diffusion into the gas system. When the trap opens, circulation through the pressure vessel is again established, as described above.

It will be obvious to those skilled in the art that various other changes may be made in the construction and arrangement without departing from the spirit of the invention and therefore the invention is not limited to what is shown

in the drawing and described in the specification but only as indicated in the following claims.

What is claimed is,

1. The method of refrigerating with a system containing a refrigerant fluid and an additional fluid for equalizing pressure which includes, circulating an excess of said additional fluid under normal operating conditions in an auxiliary circuit communicating with said system in such manner that said excess fluid is maintained at substantially the same concentration as the additional fluid in the system, and transferring additional fluid from said auxiliary circuit into said system when the pressure in the latter increases. 80

2. The method of refrigerating with a system containing a refrigerant fluid and an additional fluid for equalizing pressure which includes, circulating an excess of said additional fluid under normal operating conditions in an auxiliary circuit communicating with said system in such manner that said excess fluid is maintained at substantially the same concentration as the additional fluid in the system, and introducing refrigerant fluid into said auxiliary circuit to displace additional fluid therefrom into said system when the pressure in the latter increases. 85

3. The method of refrigerating with a system containing a refrigerant fluid and an additional fluid for equalizing pressure which includes, circulating an excess of said additional fluid under normal operating conditions in an auxiliary circuit communicating with said system, and introducing refrigerant fluid from said system into said circuit and decreasing circulation in said 100 circuit upon increase of pressure in the system whereby excess additional fluid is displaced into said system. 105

4. The method of refrigerating which includes, circulating an auxiliary fluid in a continuous circuit, evaporating cooling fluid by diffusion in one portion of said circuit, absorbing cooling fluid out of the resulting gas mixture in another portion of said circuit, flowing an excess of said auxiliary fluid in a path shunting the absorbing 115 portion of said circuit, and decreasing flow in said path and introducing cooling fluid therein to displace excess auxiliary fluid into said circuit responsive to increase of pressure in the latter. 120

5. The method of refrigerating with an absorption system having an evaporator and absorber which includes, circulating an auxiliary fluid in continuous circuit through said evaporator and absorber, evaporating cooling fluid by 130 diffusion in said evaporator, absorbing cooling fluid out of the resulting gas mixture in said absorber, circulating an excess of said auxiliary fluid in a second circuit communicating with first said circuit, and decreasing flow in said second circuit and introducing cooling fluid therein to displace excess auxiliary fluid into the first said circuit responsive to increase of pressure in the latter. 135

6. A refrigerating system including, a generator, a condenser, an evaporator, and an absorber interconnected for the circulation of a cooling fluid, said evaporator and absorber being interconnected in a continuous circuit for an auxiliary fluid, a second circuit for an excess of auxiliary 140 fluid communicating with the first said circuit, a vent connection from the discharge end of said condenser to said second circuit, and means for stopping circulation in said second circuit responsive to rise of pressure in the system. 145

7. A refrigeration system comprising a generator, air cooled condenser, evaporator, and absorber connected for circulation of refrigerant fluid, said evaporator and absorber being interconnected to form a main circuit for inert gas, means forming an auxiliary circuit for inert gas branching from said main circuit, a vent from said condenser connected to said auxiliary circuit, the highest point of said auxiliary circuit being in one portion thereof between said vent connection and said main circuit, an enlarged chamber in said portion, a liquid drain from said chamber to the path of liquid refrigerant fluid from said condenser to said evaporator, and a seal-forming liquid trap in the other portion of said auxiliary circuit, said chamber and second portion of the auxiliary circuit being cooled by air. 80
8. A refrigeration system comprising a generator, air cooled condenser, evaporator, and absorber connected for circulation of refrigerant fluid, said evaporator and absorber being interconnected to form a main circuit for inert gas, means forming an auxiliary circuit for inert gas branching from said main circuit, a vent from said condenser connected to said auxiliary circuit, the highest point of said auxiliary circuit being in one portion thereof between said vent connection and said main circuit, a gas storage chamber in said portion, and a seal-forming liquid trap in the other portion of said auxiliary circuit, said other portion being cooled by air. 85
9. A refrigeration system comprising a generator, air cooled condenser, evaporator, and absorber connected for circulation of refrigerant fluid, said evaporator and absorber being interconnected to form a main circuit for inert gas, means forming an auxiliary circuit for inert gas branching from said main circuit, a vent from said condenser connected to said auxiliary circuit, the highest point of said auxiliary circuit being in one portion thereof between said vent connection and said main circuit, and a seal-forming liquid trap in the other portion of said auxiliary circuit, said other portion being cooled by air. 90
10. A refrigeration system comprising a generator, condenser, evaporator, and absorber connected for circulation of refrigerant fluid, said evaporator and absorber being interconnected to form a main circuit for inert gas, means forming an auxiliary circuit for inert gas branching from said main circuit, a vent from said condenser connected to said auxiliary circuit, the highest point of said auxiliary circuit being in one portion thereof between said vent connection and said main circuit, and a seal-forming liquid trap in the other portion of said auxiliary circuit. 100
11. In an absorption refrigeration system containing a refrigerant fluid and an additional fluid for equalizing pressure, an air cooled condenser, a main circuit for said additional fluid, an auxiliary circuit for excess additional fluid branched from said main circuit, a vent from said condenser connected to said auxiliary circuit, the highest point of said auxiliary circuit being in one portion thereof between said vent connection and said main circuit, an enlarged chamber in said portion, and a seal-forming liquid trap in the other portion of said auxiliary circuit. 115
12. In an absorption refrigeration system containing a refrigerant fluid and an additional fluid for equalizing pressure, a condenser, a main circuit for the additional fluid, an auxiliary circuit for excess additional fluid branched from said main circuit, a storage chamber in said auxiliary circuit, and means for displacing additional fluid from said auxiliary circuit into said main circuit including means for stopping circulation in said auxiliary circuit. 120
13. In an absorption refrigeration system containing a refrigerant fluid and an additional fluid for equalizing pressure, a condenser, a main circuit for the additional fluid having a branch circuit for excess additional fluid, a vent from said condenser connected to said branch circuit, an upward loop in said branch circuit on one side of said vent connection thereto, and a seal-forming liquid trap in said branch circuit on the other side of said vent connection. 125
14. In an absorption refrigeration system containing a refrigerant fluid and an additional fluid for equalizing pressure, a condenser, a main circuit for additional fluid having a branch circuit for excess additional fluid, a vent from said condenser connected to said branch circuit, an upward loop in said branch circuit on one side of said vent connection thereto, an enlarged chamber in the upward loop side of said branch circuit, and a seal-forming liquid trap in said branch circuit on the other side of said vent connection. 130
15. In an absorption refrigeration system containing a refrigerant fluid and an additional fluid for equalizing pressure, an air cooled condenser, a main circuit for additional fluid having a branch circuit for excess additional fluid, a vent from said condenser connected to said branch circuit, an upward loop in said branch circuit on one side of said vent connection thereto, and a seal-forming liquid trap in said branch circuit on the other side of said vent connection, the latter being cooled by air. 135
16. In an absorption refrigeration system containing a refrigerant fluid and an additional fluid for equalizing pressure, a main circuit for the additional fluid, an auxiliary circuit for excess additional fluid branched from said main circuit, and means for displacing additional fluid from said auxiliary circuit into said main circuit including means for stopping circulation in said auxiliary circuit. 140
17. In an absorption refrigeration system containing a refrigerant fluid and an additional fluid for equalizing pressure, a main circuit for the additional fluid, an auxiliary circuit for excess additional fluid branched from said main circuit, and means utilizing refrigerant fluid for displacing additional fluid from said auxiliary circuit into said main circuit including means for stopping circulation in said auxiliary circuit. 145
18. In an absorption refrigeration system containing a refrigerant fluid and an additional fluid for equalizing pressure, a main circuit for the additional fluid, an auxiliary circuit for excess additional fluid branched from said main circuit, and means utilizing refrigerant fluid for displacing additional fluid from said auxiliary circuit into said main circuit including a seal-forming liquid trap for stopping circulation in said auxiliary circuit. 150
19. In an absorption refrigeration system containing a refrigerant fluid and an additional fluid for equalizing pressure, a main circuit for the additional fluid, an auxiliary circuit for excess additional fluid branched from said main circuit, a storage chamber in said auxiliary circuit, and means for displacing additional fluid from said auxiliary circuit into said main circuit including 155

means for stopping circulation in said auxiliary circuit.

20. In an absorption refrigeration system containing a refrigerant fluid and an additional fluid for equalizing pressure, a condenser, a main circuit for said additional fluid, an auxiliary circuit for excess additional fluid branched from said main circuit, a vent from said condenser to said auxiliary circuit, and means for stopping circulation in said auxiliary circuit upon increase in temperature of said condenser.

21. In an absorption refrigeration system containing a refrigerant fluid and an additional fluid for equalizing pressure, an air cooled condenser, a main circuit for said additional fluid, an auxiliary circuit for excess additional fluid branched from said main circuit, a vent from said condenser to said auxiliary circuit, and means for stopping circulation in said auxiliary circuit upon increase in temperature of the air.

22. In an absorption refrigeration system containing a refrigerant fluid and an additional fluid for equalizing pressure, an air cooled condenser, a main circuit for said additional fluid, an auxiliary circuit for excess additional fluid branched from said main circuit, a vent from said condenser to said auxiliary circuit, and a seal-forming liquid trap in said auxiliary circuit exposed for air cooling to stop circulation upon increase in temperature of said condenser.

23. In an absorption refrigeration system containing a refrigerant fluid and an additional fluid for equalizing pressure, an air cooled condenser, a main circuit for said additional fluid, an auxiliary circuit for excess additional fluid branched from said main circuit, an enlarged chamber in said auxiliary circuit, a vent from said condenser to said auxiliary circuit, and a seal-forming liquid trap in said auxiliary circuit exposed for air cooling to stop circulation upon increase in temperature of said condenser.

24. That improvement in the art of refrigeration with a system containing a refrigerant fluid and an auxiliary gas for equalizing pressure which comprises storing an excess of said gas at sub-

stantially the same partial pressure as that of gas in the system under normal operating conditions and circulating the stored gas in the system when the pressure in the system increases.

25. That improvement in the art of refrigeration with a system containing a refrigerant fluid and an auxiliary gas for equalizing pressure which comprises storing an excess of said gas at substantially the same partial pressure as that of gas in the system under normal operating conditions, displacing said excess by refrigerant fluid when the pressure in the system increases, and circulating the displaced gas in the system.

26. The method of refrigeration which includes, circulating a pressure equalizing gas in continuous circuit, evaporating refrigerant fluid in one portion of said circuit, absorbing refrigerant fluid in another portion of said circuit, storing an excess of pressure equalizing gas at substantially the same partial pressure as that of gas in said circuit during normal operating conditions, and circulating the stored gas in said circuit upon increase of pressure.

27. That improvement in the art of refrigeration by evaporation of refrigerant fluid into a working quantity of inert gas which comprises maintaining an auxiliary quantity of inert gas at substantially the same partial pressure as that of gas in said working quantity during normal operating conditions and adding to the working quantity from said auxiliary quantity to increase the pressure of the former.

28. The method of refrigeration which includes circulating a pressure equalizing fluid in two continuous circuits having a portion in common, evaporating refrigerant fluid in one portion of the first of said circuits, absorbing refrigerant fluid in another portion of said circuit, and introducing refrigerant vapor into the second of said circuits and stopping circulation therein to displace pressure equalizing gas into said first circuit to increase the pressure in the latter.
